UNITED STATES PATENT OFFICE.

EUGENE P. CONNELLY, OF BOSTON, MASSACHUSETTS

REFRIGERATING APPARATUS.

1,172,873.

Specification of Letters Patent. Patented Feb. 22, 1916.

Application filed January 23, 1915. Serial No. 3,939.

To all whom it may concern:

Be it known that I, EUGENE P. CONNELLY, a citizen of the United States, and a resident of Boston, in the county of Suffolk and 5 State of Massachusetts, have invented certain new and useful Improvements in Refrigerating Apparatus; and I do hereby declare the following to be a full, clear, and exact description of the invention, such as 10 will enable others skilled in the art to which it appertains to make and use the same.

This invention relates to an improvement in refrigerating apparatus, one object being to provide improved means for automatically 15 maintaining the liquefied gas under pressure and feeding same through an expansion valve into the freezing or refrigerating coil.

A further object is to provide improved 20 means for withdrawing the gas at intervals from the refrigerating coils and for forcing it into the storage cylinder, and also for replenishing the air supply by which the pressure on the liquefied gas within the pressure 25 cylinder is maintained.

With these and other ends in view my invention consists in the parts and combination of parts and in the details of construction as will be more fully explained and 30 pointed out in the claims.

The accompanying drawings, Figure 1 is a diagrammatic view in elevation, partly in section of my apparatus, and Fig. 2 is a similar view of a modified form.

35 1 represents an air compressor, 2 a gas compressor and 3 a water pump, located side by side, with their pistons connected by rods to the crank shaft 4 which carries a gear 5 in mesh with the smaller gear 6 on shaft 7, 40 the latter carrying a hand crank 8 for rotating shaft 4. It is evident however that the same results could be accomplished by locating them in other positions, and actuating them by any approved form of motors and 45 gearing.

Leading from the gas compressor 2 is the pipe 9, which is connected to one end of a condenser coil 9, which is cooled by a water spray from a spraying pipe 10 connected 50 with pump 3, and which liquefies the ammonia gas, and leading from the other end of said condenser coil 9, is the pipe 11 which discharges the liquid into the top of the water cooled storage cylinder 12, a valve 13

being located in pipe 11 between coil 9 and cylinder 12 to prevent the flow of liquid from the cylinder back to the condenser coil.

14 is a pipe communicating with cylinder 12 near the top thereof and provided at 15 with an expansion valve. This pipe is connected with one end of the freezing or refrigerating coil 16, while the opposite end of the latter is connected by pipe 17 to receiver 18, the pipe 17 being provided with releasing valve 19 of any approved form for 60 maintaining a uniform pressure in the coil 16, and preventing the accumulation of back pressure within the coils 16. This valve 19 can be so adjusted to maintain a uniform pressure within the coil, by permitting any 65 excess to escape past valve into the receiver 18. The receiver is of a size sufficient to store all the gas that may pass into same, by reason of the excess of back pressure. The receiver 18 is of size sufficient to take care 70 of all the gas used during a reasonable period of time. With the relief valve set to release at that pressure in coils 16 which will give the best cooling effect, a uniform pressure and temperature will be maintained in 75 the coils. As the excess pressure in coils escapes into the receiver, the pressure in the latter will rise, and if the receiver be of sufficient size to accommodate all the gas stored 80 in cylinder 12, it is apparent that the pressure in the receiver would never equal the pressure in the coils. It is not however necessary or desirable to use a receiver to accommodate all the gas, but one of size sufficient 85 to maintain the proper temperature for a reasonable length of time. As the excess of pressure is released, the pressure in the receiver will continue to increase until it equals that in the coils. Up to this period a uniform temperature and pressure will be 90 maintained in the coils, but as the liquefied gas still continues to be discharged from cylinder 12, it is apparent that the pressure in 95 the coils and also the receiver will continue to rise but owing to the increasing pressure 100 a uniform temperature would not be maintained. The object of the receiver is to maintain a uniform pressure and temperature for a longer period than would otherwise be possible.

105 Leading from the receiver 18 to the gas compressor 2 is the pipe 20 provided with the stop valve 21, which regulates the flow

of gas from the receiver to the gas compressor, and the gas compressor 2 is provided at its lower end with a spring controlled valve 22 which opens upwardly so that as the piston rises it draws in the gas through pipe 20. The cylinder 2, is also provided at its bottom with a spring actuated valve 23 which opens downwardly and which controls the flow of gas between the 10 compressor 2 and the cooling coil 9. From the foregoing it will be seen that as the piston in cylinder 2 rises, valve 22 will open and permit the gas to be drawn from the receiver 18 into the compressor 2 and valve 15 23 will close thus preventing any gas within coil 9 from being drawn back into the compressor, and as the said piston descends valve 22 will close and valve 23 open, thus permitting the compressed gas to pass into 20 the coil 9.

Leading from the bottom of air compressor 1, to the air reservoir 24, is the pipe 25 provided with a valve 26 for preventing the back flow of air, and communicating with 25 the reservoir 24, through pipe 27, is the compression cylinder 28. The compression cylinder is located in the plane of the storage cylinder 12, and carries a piston 29, which is connected to piston 30 in the storage cylinder 12 by the piston rod 31. Piston 29 is of greater diameter than piston 30, and as they are rigidly connected by the rod 31, the piston 30 necessarily follows the movement of the piston 29. Cylinder 28 is provided at its upper end with a vent pipe 32. Pipe 27, which connects the reservoir 24 with the compression cylinder 28 is provided with a reducing valve 33.

In the operation of the apparatus ammonia gas is forced by the compressor 2 into condenser coil 9 where it is liquefied and passes from thence, in liquid form, into storage cylinder 12. After the cylinder 12 has been filled with the liquefied gas at high 40 pressure, the gas is still further compressed by admitting compressed air to the underside of piston 29. The pressure against piston 29 is always sufficient to maintain the liquid in cylinder 12 under compression and prevent any expansion of the latter and also 45 prevents passage of ammonia vapor to the refrigerating coil. After the proper pressure of the liquefied gas in the cylinder 12 has been attained, the expansion valve 50 15 is opened thus permitting the liquid in the cylinder to gradually escape into the refrigerating coil, where it is vaporized and by its rapid expansion produces a low temperature in the coils in the well known manner. The liquid escapes slowly from the cylinder 12, but as the pressure on piston 29 is always in excess of the pressure on piston 30, the latter is gradually forced upwardly, thus holding the liquefied gas, irrespective of the quantity thereof in the stor- 60 65

age cylinder, under a regular and unvarying pressure. As the liquefied gas leaves the expansion valve 15 and enters the coil 16 it is rapidly vaporized and expands and spreads out through the coil. 70

The cylinder 12 is of sufficient capacity to supply gas to the coil for a certain length of time, which of course can be increased or decreased by varying the size of the cylinder, or by adjusting valve 15. After the apparatus has exhausted itself, or in other words, after all the liquid in cylinder 12 has passed into the refrigerating coil 16, the air is exhausted from cylinder 28 and the compressors 1 and 2 and pump 3 started. The 75 operation of the compressor 2 sucks or withdraws the gas from the receiver 18 through pipe 20 into the compressor 2 and from thence forces it through condenser 9 and into the storage cylinder 12 in liquid form 80 under pressure, while the air compressor 1 restores the air pressure in reservoir 24. Instead of using an air pump or compressor 1, air could be supplied to a reservoir 24 from an accumulator which would operate to 85 maintain the air in said reservoir at an even pressure from the commencement to the end of the operation, and instead of using air at all for maintaining the liquid in compression tank 12 under compression water under 90 hydrant or other pressure may be used in compression cylinder 28.

Instead of carrying the refrigerating coils into the refrigerator or other cooling apartment, where the leakage of ammonia gas 100 would spoil the food, I may use the refrigerating coil 16 to cool brine which is circulated in the refrigerator. Such construction is shown in Fig. 2, wherein I have shown the refrigerating coil 16 located within the brine tank 33^a for cooling the brine therein. Tank 33^a is provided with a pipe 34, having a valve 35 therein, through which the brine passes to the cooling or refrigerating coil 16^a located within the refrigerator 110 or other compartment, and with a pipe 36, through which the brine returns from coil 16^a to the brine tank adjacent the top thereof, a pump 37 being connected with the return pipe 36 for forcing circulation. With 115 this construction, as in the previous one, the excess of back pressure of gas in pipe 17 escapes into the receiver 18 and passes from thence back to the compressor.

This device may be used for commercial 120 or domestic use, and its construction is such that the compressor or pumps 1 and 2 are used only in re-liquefying the gas and putting it under pressure in cylinder 12 and for replenishing the air reservoir 24. 125

It is evident that many slight changes might be resorted to in the relative arrangement of parts shown and described without departing from the spirit and scope of my invention. Hence I would have it under- 130

stood that I do not wish to confine myself to the exact construction and arrangement of parts shown and described, but

Having fully described my invention what I claim as new and desire to secure by Letters-Patent, is:—

1. In a refrigerating apparatus, the combination of a gas compressor, a condenser, a storage cylinder into which the liquefied gas is forced by the gas compressor, a refrigerating coil connected with the top of said storage cylinder and with the gas compressor, an expansion valve intermediate the storage cylinder and the refrigerating coil, a piston at the bottom of said storage cylinder and means for actuating said piston whereby the liquefied gas in said cylinder is maintained under constant pressure and the passage of ammonia vapor to refrigerating coil prevented. 50
2. In refrigerating apparatus, the combination of a gas compressor, a storage cylinder, a condenser intermediate the compressor and cylinder and communicating with both, a refrigerating coil connected at one end with the top of said storage cylinder and at the other end with the compressor, an expansion valve intermediate the storage cylinder and refrigerating coil, a piston at the bottom of the storage cylinder, a piston rod connected with said piston and carrying a larger piston at its other end, a cylinder for said larger piston, and means for supplying a pressure fluid to said last-mentioned cylinder whereby the fluid in the storage cylinder is maintained under constant pressure, and the passage of ammonia vapor from said storage cylinder to the refrigerating coil prevented. 60
3. In refrigerating apparatus, the combination with a gas compressor, a storage cylinder, a condenser intermediate said compressor and cylinder and communicating with both, a refrigerating coil connected at one end with the top of the storage cylinder and at its other end with the compressor and an expansion valve intermediate the storage cylinder and refrigerating coil, of a piston at the bottom of the storage cylinder, a rod connected with said piston, a larger piston 55 on the other end of said rod, an air cylinder in which said larger cylinder works, an air reservoir in communication with said air cylinder, an air compressor and a pipe leading from said air compressor to the air reservoir. 65
4. In refrigerating apparatus, the combination of a gas compressor, a condenser, a storage cylinder into which the liquefied gas is forced by the gas compressor, a refrigerating coil connected with the top of said storage cylinder and with a receiver, a relief valve in the pipe leading to the receiver, a pipe connecting the receiver and the gas compressor, an expansion valve intermediate the storage cylinder and the coil, a piston at the bottom of said storage cylinder and means for actuating said piston whereby the liquefied gas in said cylinder is maintained under constant pressure and the passage of ammonia vapor to the refrigerating coil prevented. 70
5. In refrigerating apparatus, the combination of a gas compressor, a condenser, a storage cylinder into which the liquefied gas is forced by the compressor, a refrigerating coil connected with the top of said storage cylinder and with the gas compressor and passing through a brine tank, an expansion valve intermediate the storage cylinder and the refrigerating coil, a piston at the bottom of said storage cylinder, means for actuating said piston whereby the liquefied gas in said cylinder is maintained under constant pressure, and a coil communicating with said brine tank. 80

In testimony whereof, I have signed this specification in the presence of two subscribing witnesses.

EUGENE P. CONNELLY.
